BRAKE DRUM

Fred E. Cooper, Tulsa, Okla.

Application March 5, 1934, Serial No. 714,171

15 Claims. (Cl. 188—264)

This invention relates to improvements in brake drums, and more particularly to a braking mechanism and reel structure for hoisting machinery, in which braking mechanism is used in lowering heavy loads to control the rate of travel.

In hoisting machinery of this character, the external or contracting type of brake is ordinarily used, and such brake generally consists of a continuous brake band which engages the external surface of the brake drum when the brake is in operation. Due to the close proximity of the brake band to the braking surface of the drum and the large area of this surface covered by the brake band, very little air comes in contact with the braking surface, thus making it difficult to dissipate the heat absorbed by the periphery of the drum during the braking operation. Furthermore, as the outer edges of the drum periphery are in contact with the air, the heat from this portion of the drum will be dissipated more readily, and consequently, the outer edges of the drum will be cooler than the central portion covered by the brake band. This results in unequal expansion of the metal in the drum periphery; causes distortion of the braking surfaces from a true circle; impairs the efficiency of the brake; and also causes the metal to crack and check due to unequal expansion.

Various types of drums have been made heretofore in an attempt to provide an efficient circulation of the air therethrough for dissipating the heat generated by the frictional contact of the band with the drum. Some of the structures heretofore proposed have incorporated in them a system or series of spokes arranged fanwise in an attempt to obtain a movement of the air against the inside of the peripheral member of the drum for the dissipation of heat, but all such structures have proven inefficient, as their action tends to set up local eddy currents within the drum structure, and fail to develop a continuous supply of cooler air against the drum periphery.

It is therefore the primary object of my invention to provide a drum which will create a constant movement of cool air against the inner surface of the peripheral member of the drum, so as to obtain efficient dissipation of heat, and maintain a temperature which will prevent injury to the braking surface or the lining of the brake drum.

Another object is to provide a brake drum structure designed to direct the movement of the air against the periphery of the drum so as to maintain a uniform temperature throughout, and

prevent distortion of the braking surface from its correct contour.

A further object is to furnish a brake drum structure that will permit equal expansion and contraction of the peripheral member of the drum under temperature variations without distorting the braking surface of said drum.

A still further object is to supply a reel and brake drum structure wherein the load stresses are confined to an integral member, so as to avoid bolted or riveted joints being subjected to severe working stresses and causing them to work loose and fail in service.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a perspective view showing a pair of my improved braking drums forming part of hoisting machinery.

Fig. 2 is a longitudinal elevation partly in vertical section of the reel and brake drum assembly.

Fig. 3 is an end elevation of one of my improved drums.

Fig. 4 is a similar view of the opposite side of my improved brake drum, taken on the line 4—4 of Fig. 2.

Fig. 5 is a cross sectional view taken on the line 5—5 of Fig. 3.

In the drawings, 6, 6 designates a pair of brake drums, each in the form of an integral structure, 35 consisting of a central hub 7 having a laterally extending annular flange 8, and a radially projecting flange 9, the latter terminating in a rim or peripheral member 10, the outer surface of which forms the braking surface upon which the 40 brake band 11 contacts when the brake is applied.

A plurality of blades or impeller vanes 12 extend outwardly from the hub 7, and terminate in the rim 10. These blades have a substantially spiral contour of a nature which will promote the 45 displacement of air by centrifugal action. A plurality of relatively short auxiliary blades 13, having a contour similar to that of the main blades 12, extend inwardly from the rim 10 and are spaced between the main blades 12 as well as 50 from the hub 7. Both sets of blades are enclosed within the drum, adjacent to the rim, by the radial flange 9, a relatively short internal flange 14 and the rim 10, thereby forming multiple air 55 passages within the brake drum structure.

- The flange 9 is provided with a series of multiple air intake openings 15 adjacent to the hub 7. A series of multiple air discharge openings 16 are also provided in each of the flanges 9 and 14 adjacent the rim 10 and the blades 12 and 13, and these discharge openings communicate with the air passages within the drum for the purpose of discharging air from said air passageways.
- By way of example, I have shown in the drawings a pair of my improved brake drums forming part of the braking mechanism for hoisting machinery, wherein the drums are mounted on a stationary shaft 17 which may be secured in position in suitable brackets or supports 18. Suitable bearings 19, having cover plates 20, may be interposed between the shaft and the hub 7 of the drums to permit the latter to rotate freely on the shaft in either direction.
- A cylindrical reel or spool 21 is interposed between the drums, and this reel is mounted on and suitably secured to the annular flanges 8 projecting from the drums. Tie rods 22 pass through the brake drums and cover plates 20, and extend continuously through the drum reel 21 for holding the various unit parts firmly in their respective positions as shown in Fig. 2.
- Any suitable driving mechanism, such as a gear or chain sprocket 23 may be suitably secured by means of bolts 23' to either one of both drums for rotating the latter. For the purpose of securing the rope or cable to the brake drum structure, I provide a slot 24 in the side wall of one of the drums, and by this arrangement, the power is transmitted from the driving mechanism 23 to the rope or cable (not shown), without subjecting the assembled joints of the mechanism to heavy torsional strains.
- When the drums are rotating, the air in the air passages of each of said drums is set in motion by the blades 12 and 13, and due to the centrifugal action caused by said blades, the air is thrown out toward and against the inside of the rim 10, and passes out through the discharge openings 16.
- As the air in the chambers or passageways is moved outwardly by centrifugal action, a partial vacuum is formed in the part of the air passages adjacent to the intake openings 15 and annular opening 25, whereby a fresh supply of cool air is sucked into the drum through said openings and is in turn displaced by centrifugal action and forced against the inside of the rim 10 and discharged through the openings 16.
- This action produces a continuous flow of air from the openings 15 and 25 to and against the inside of the rim 10 and out through the openings 16.
- As above stated, due to the fact that the edges of the rim 10 are in contact with the atmosphere and will therefore be cooled more quickly than the center of the rim which is removed from atmospheric contact when covered by the brake band, I provide means for concentrating the air, driven by the blades, against the central portion of the rim. For example, I may incline the outer portion of the internal flange 14 inwardly, as shown at 26 for the purpose of directing the air against the center of the rim. By thus concentrating the air flow, the heat generated by the braking action and absorbed by the rim is uniformly dissipated throughout its width, and consequently, by maintaining a uniform temperature throughout the area of the rim, warpage and distortion of the latter due to unequal expansion and contraction of the metal, is prevented.
- Each drum may be provided with the conventional band retaining external ridge 50, and it will be noted that the inclined surface 26 functions not only to concentrate the centrifugally driven air against the medial portion of the rim, but also to direct it toward the flange 50 to insure the cooling of the inner side of the drum.
- In brake drum structures heretofore proposed, a continuous movement of the air therethrough is not obtained due to the absence of enclosed air chambers. In my structure, a continuous flow is maintained by the addition of the internal flange 14 in combination with the discharge ports 16 and the intake ports 15 and 25. Unless the internal flange 14 is employed in a structure of this character, it is impossible to obtain effective circulation of cool air within the drum, due to eddy currents which will be set up within the brake drum structure.
- The internal flange 14 also acts as a reinforcing member in the same manner as the flange 9 to prevent any inward movement of the rim 10 between the main blade supports when heavy external pressure is exerted when the brake is applied. This flange also provides additional radiation area for the dissipation of heat, and is equivalent in this respect to the flange 9 on the opposite side of my improved brake drum.
- The auxiliary blades or impeller vanes 13 which extend inwardly from the rim 10 are positioned laterally between the flanges 9 and 14, and these blades serve to stimulate the movement of the air against the rim, and provide a more uniform distribution against said rim. These blades also serve the dual purpose of reinforcing the rim 10 between the points of contact of said rim with the main blades 12, and provide additional radiation surface for the dissipation of heat.
- In the operation of my device, it will be clear that as the drum rotates, air will be sucked into the drum through the openings 15 on one side of the drum and the annular opening 25 at the opposite side thereof, and this air will be forced against the center of the rim by the main blades 12, and discharged from said drum through the openings 16.
- It will be obvious that the constant circulation of air through the drum in this manner will maintain the braking surface at an even and low temperature, and thereby avoid any damage to the rim surface which might be caused by excessive heat when the brake is applied.
- This brake drum may be applied to any mechanism requiring a retarding device for its successful operation. The brake drum can and will be used on other types of machinery other than hoisting machinery, and can be mounted directly on a shaft and secured thereto, and does not necessarily have to be used in combination with a reel member as exemplified in the application.
- While I have disclosed what I now consider to be a preferred embodiment of the invention in such manner that the same may be readily understood by those skilled in the art, it is apparent that changes may be made in the details disclosed, without departing from the spirit of the invention, as expressed in the claims.
- What I claim and desire to secure by Letters Patent is:
1. A brake drum comprising a hub, a peripheral member and opposite side members rigidly united with one another and forming an internal substantially circular chamber, means in the drum

- adjacent to the hub to admit air into said chamber, ports in the side members adjacent to the peripheral member for discharging air from said chamber, and blades within the drum for drawing air in through said means, forcing it toward the peripheral member and discharging it through said ports, the interior of said peripheral member being substantially cylindrical and unobstructed transversely of the drum to cause air, 5 centrifugally forced by the blades, to move laterally across the central portion of said inner surface before discharging through said ports.
2. A brake drum comprising a hub, a peripheral member and opposite side members rigidly united with one another and forming an internal substantially circular chamber, means in the drum adjacent to the hub to admit air into said chamber, ports in the side members adjacent to the peripheral member for discharging air from said chamber, blades within the drum for drawing air in through said means, forcing it toward the peripheral member and discharging it through said ports, said peripheral member having its entire inner surface unobstructed transversely 10 of the drum to cause air, centrifugally forced by the blades, to move laterally across the central portion of said inner surface before discharging through said ports, and means within the drum for concentrating air, driven by the blades, 15 against the central portion of the rim.
3. A brake drum comprising a hub, a peripheral member and opposite side members rigidly united with one another and forming an internal substantially circular chamber, means in the drum adjacent to the hub to admit air into said chamber, ports in the side members adjacent to the peripheral member for discharging air from said chamber, and blades within the drum for drawing air in through said means, forcing it 20 toward the peripheral member and discharging it through said ports, said peripheral member having its entire inner surface unobstructed transversely of the drum to cause air, centrifugally forced by the blades, to move laterally 25 across the central portion of said inner surface before discharging through said ports, one of said side members having an outer portion near said peripheral member provided with an inner surface inclined in a direction toward the other side member for concentrating the centrifugally forced air against the central portion of the inner surface of the peripheral member.
4. A brake drum comprising a hub, a peripheral member and opposite side members rigidly united with one another and forming an internal substantially circular chamber, means in the drum adjacent to the hub to admit air into said chamber, ports in the side members adjacent to the peripheral member for discharging air from said chamber, blades within the drum for drawing air in through said means, forcing it toward the peripheral member and discharging it through said ports, said peripheral member having its entire inner surface unobstructed transversely 30 of the drum to cause air, centrifugally forced by the blades, to move laterally across the central portion of said inner surface before discharging through said ports, and spaced transversely positioned shorter blades extending inwardly from the peripheral member and arranged between the first mentioned blades substantially parallel to the axis of the drum for directing air driven by the first mentioned blades, through the peripheral ports.
5. A brake drum comprising a central hub member, a radial flange member extending therefrom, an annular peripheral member having one of its edge portions united with the outer edge portion of said radial flange, an internal flange member spaced from said radial flange and extending inwardly from the opposite edge portion of said peripheral member, said hub member, peripheral member and flanges being integrally united, a series of ports arranged in each flange adjacent to said peripheral member, air admission means in one of said flanges adjacent to the hub member, and impeller blades extending outwardly from said central hub member and enclosed at their outer ends by said flanges and said peripheral member, whereby a plurality of air passageways are formed in said drum between the air admission means and said ports, said peripheral member having its entire inner surface unobstructed transversely of the drum to cause air, centrifugally forced by the blades, to move laterally across the central portion of said inner surface before discharging through said ports.
6. A brake drum comprising a hub, a radial flange extending therefrom and having a plurality of air intake openings positioned adjacent to said hub, an annular peripheral member having one of its edge portions integral with the outer extremity of said radial flange, an internal flange spaced from said radial flange, and extending inwardly from the opposite edge portion of said peripheral member, both of said flanges having a plurality of air outlet ports adjacent the peripheral member, and impeller blades extending outwardly from said hub and enclosed at their outer ends by said flanges and said peripheral member, whereby a plurality of air passageways are formed in said drum, communicating with said air intake openings and air outlet ports, said peripheral member having its entire inner surface unobstructed transversely of the drum to cause air, centrifugally forced by the blades, to move laterally across the central portion of said inner surface before discharging through said ports.
7. A brake drum comprising a hub, a radial flange extending therefrom and having a plurality of air intake ports adjacent said hub, an annular peripheral member having one of its edge portions rigidly united with the outer extremity of said radial flange, an internal flange spaced from said radial flange and extending inwardly from the opposite edge portion of said peripheral member, said flanges having a plurality of air outlet ports adjacent the peripheral member, and impeller blades extending outwardly from the hub portion of said drum to the peripheral member for causing air drawn in through said intake ports to be discharged through the outlet ports, said peripheral member having its entire inner surface unobstructed transversely of the drum to cause air, centrifugally forced by the blades, to move laterally across the central portion of said inner surface before discharging through said ports.
8. A brake drum comprising a hub, a radial flange extending therefrom, a peripheral member having one of its edge portions united with the outer extremity of said radial flange, an internal flange united with the opposite edge portion of the peripheral member and extending inwardly from said member, said internal flange being spaced from said radial flange and said hub, whereby an annular air admission opening is formed adjacent to said hub, said flanges having a plurality of outlet ports adjacent the per-

peripheral member, the entire inner surface of the peripheral member being unobstructed transversely of the drum, and means for drawing air through said annular opening, forcing it against said surface and discharging it through said outlet ports.

9. A brake drum comprising a hub, a radial flange extending therefrom and having a plurality of intake ports adjacent said hub, a peripheral member having one of its edge portions united with the outer extremity of said radial flange, an internal flange extending inwardly from the opposite edge portion of said peripheral member and spaced from said radial flange and said hub, whereby an opening is formed between said hub and said internal flange, said flanges being integral with said hub and peripheral member and having a plurality of outlet ports adjacent the peripheral member, and impeller blades fixedly mounted within the drum for drawing air through said intake ports and said opening, forcing it against the peripheral member and discharging it through said outlet ports, said peripheral member having its entire inner surface unobstructed transversely of the drum to cause air, centrifugally forced by the blades, to move laterally across the central portion of said inner surface before discharging through said ports.
10. A brake drum comprising a hub, a radial flange extending therefrom, a peripheral member having one of its edge portions rigidly united with the outer extremity of said radial flange, an internal flange spaced from said radial flange and extending inwardly from said peripheral member, said internal flange being rigidly united with the opposite edge portion of said peripheral member and both flanges having a plurality of air outlet ports adjacent the peripheral member, the entire inner surface of the peripheral member being shaped to permit unobstructed flow of air laterally across said surface, and impeller blades extending from the hub to the peripheral member for causing air drawn in through said intake ports to be discharged through said outlet ports, said internal flange having the inner surface of its outer portion inclined in a direction toward the radial flange for concentrating air driven by the blades, against the central portion of the peripheral member before it is discharged through the outlet ports.

11. A brake drum comprising a hub, a radial flange extending therefrom, a peripheral member having one of its edge portions rigidly united with the outer extremity of said radial flange, an internal flange spaced from said radial flange and extending inwardly from said peripheral member and rigidly united with the opposite edge portion of the peripheral member, impeller blades extending outwardly from said hub, said flanges and peripheral member enclosing the outer end portions of said blades to form substantially radial air passageways in said drum, spaced shorter blades connecting said flanges and extending inwardly from said peripheral member, said shorter blades being arranged between said impeller blades and positioned substantially parallel to the axis of the drum, said flanges having a plurality of air discharge ports arranged adjacent said peripheral member and communicating with said air passageways and with the spaces between the shorter blades, and means at the hub portion of the drum for admitting air into said passageways.

12. A brake drum comprising a hub, a peripheral member, a radial flange extending from said hub and connecting the latter to said peripheral member, blades extending outwardly from said hub and terminating in said peripheral member, said blades forming a plurality of radially arranged air passageways around said hub, an internal flange spaced from said radial flange and extending inwardly from said peripheral member, one of said flanges being provided with means adjacent said hub and communicating with said passageways for admitting air into said passageways, spaced shorter blades extending inwardly from said peripheral member, connecting said flanges and projecting into said passageways, said shorter blades being positioned parallel to the axis of the central hub, and said flanges having ports arranged adjacent said peripheral member and said shorter blades and communicating with said passageways for discharging air from said passageways and from the spaces between the shorter blades.

13. A brake drum comprising a hub, a flange disc having its central portion rigidly united with said hub, a rim having one of its side edge portions rigidly united with the outer edge portion of the disc, an annular internal flange spaced from the disc and having its outer edge portion rigidly united with the other edge portion of the rim, the periphery of said rim forming an annular braking surface, a ridge projecting from said surface in substantial alignment with the disc, substantially radially disposed blades in the drum dividing the interior of the drum into pockets and forming means for forcing air from the hub portion of the drum, through said pockets and against the inner surface of the rim, the entire inner surface of the rim being shaped to permit unobstructed flow of air across the interior of the rim, means at the hub portion of the drum for admitting air into said pockets, ports in the disc and flange positioned in close proximity to said rim for discharging air from the pockets to both sides of the drum, and means within the drum for directing air, driven by the blades, against the central portion of the rim.

14. A brake drum comprising a hub, a flange disc having its central portion rigidly united with said hub, a rim having one of its side edge portions rigidly united with the outer edge portion of the disc, an annular internal flange spaced from the disc and having its outer edge portion rigidly united with the other edge portion of the rim, the periphery of said rim forming an annular braking surface, a ridge projecting from said surface in substantial alignment with the disc, substantially radially disposed blades in the drum dividing the interior of the drum into pockets and forming means for forcing air from the hub portion of the drum, through said pockets and against the inner surface of the rim, the entire inner surface of the rim being shaped to permit unobstructed flow of air across the interior of the rim, means at the hub portion of the drum for admitting air into said pockets, ports in the disc and flange positioned in close proximity to said rim for discharging air from the pockets to both sides of the drum, and means within the drum for directing air, driven by the blades, against the central portion of the rim, and shorter spaced blades arranged transversely of the drum between said first mentioned blades and projecting centrally from the peripheral member, all of

said blades being integrally connected with the rim, disc and internal flange.

15. A brake drum comprising a central hub member, an annular peripheral member, a radial flange connecting said hub to said peripheral member, a plurality of impeller blades extending outwardly from said hub and terminating in said peripheral member, said blades forming a plurality of radially arranged air passageways around said hub, an internal flange spaced from said radial flange and extending inwardly from said peripheral member, said flanges and peripheral member enclosing the outer portions of said blades, said flanges being provided with a plurality of air intake ports adjacent said

hub member and communicating with said air passageways for the admission of air thereto, auxiliary blades extending inwardly from said peripheral member and projecting into said air passageways, said auxiliary blades being arranged parallel to the axis of the hub member, said internal flange having its outer portion extending toward the radial flange for directing air in said passageways toward the central portion of the peripheral member, and outlet ports in said flanges adjacent the peripheral member, said first mentioned blades being adapted to cause air to circulate from said intake ports to said outlet ports through said passageways.

FRED E. COOPER. 15
